(57) **ABSTRACT**

A seawall constructed to provide an improved installation method and further provide a more resistant structure wherein the elements of the present invention are combined with an ultra high performance concrete to create the seawall of the present invention. The seawall includes a plurality of wall panel members wherein the wall panel members have a plurality of cells formed therein wherein the cells are hollow and extend between the upper edge and lower edge of the wall panel member. Wall panel connection members are configured to mateably couple adjacent wall panel members. The present invention further includes piling members configured to be journaled into the cells of the wall panel members and penetrate the ground underneath the wall panel member. A sub-cap member is superposed the wall panel member and is integrally formed therewith subsequent pouring of concrete. A top cap member is operably coupled to the sub-cap member.

SEAWALL

FIELD OF THE INVENTION

The present invention relates generally to marine-land barriers, more specifically but not by way of limitation, a seawall that is configured to be constructed employing a plurality of elements and techniques that facilitates a secure and cost effective installation wherein the present invention further utilizes materials such as but not limited to ultra-high performance concrete and fiber reinforced polymers.

BACKGROUND

Seawalls are a structure that is installed as a form of defense constructed in coastal areas where the sea directly impacts the landforms. There are several different types of seawalls that are commonly constructed and they are chosen based on the reflection of forces to which they will be subjected as well as the cost associated for each type. Depending on the type of seawall construction inevitably there will be problems and failures based upon the conditions to which they are subjected, construction techniques and components thereof. One issue is anchor rod deterioration wherein prolonged exposure to saltwater and other elements can cause anchor rod failure, which leads to seawall misalignment and outward movement.

Another issue with conventional seawall construction is the issue with seawall cap failure. Exposure to saltwater and other elements can cause the steel utilized for reinforcing the concrete seawall cap to corrode, which causes expansion. This results in the development of cracks, which eventually leads to the breaking off of large pieces of the seawall cap. The loss of concrete and exposure of the corroding reinforcing steel weakens the seawall cap significantly leads to further seawall misalignment and other structural issues. In addition to the aforementioned issues, there are disadvantages to conventional seawall construction that result in a more costly and timely installation.

Accordingly, there is a need for a seawall and construction thereof that facilitates a cost effective installation thereof and further provides improved construction techniques so as to provide a superior seawall.

SUMMARY OF THE INVENTION

It is the object of the present invention to provide a seawall that is configured with a plurality of elements facilitating an improved installation and a durable seawall wherein the present invention includes a plurality of wall panels being operably coupled with wall panel connection members.

Another object of the present invention is to provide a seawall that is installed so as to protect a landform from marine conditions wherein the present invention includes a piling member that is inserted into some cells of the wall panel and driven downwards so a portion thereof is deeper than the bottom of the wall panel.

A further object of the present invention is to provide a seawall that is configured with a plurality of elements facilitating an improved installation and a durable seawall wherein some of the cells of the wall panels have disposed therein pour plugs wherein the pour plugs are secured utilizing chemical adhesion.

Still another object of the present invention is to provide a seawall that is installed so as to protect a landform from marine conditions wherein the present invention wherein the

2

wall panels have superposed thereto sub-cap sections wherein the sub-cap sections are secured utilizing chemical adhesion.

An additional object of the present invention is to provide a seawall that is configured with a plurality of elements facilitating an improved installation and a durable seawall wherein the sub-cap section includes pour blocks wherein the pour blocks are located at the ends of the sub-cap sections and are secured utilizing chemical adhesion.

Yet a further object of the present invention is to provide a seawall that is installed so as to protect a landform from marine conditions wherein the present invention wherein the wall panels further include tie back rods that are secured utilizing high strength adhesive.

Another object of the present invention is to provide a seawall that is configured with a plurality of elements facilitating an improved installation and a durable seawall wherein ensuing installation of the sub-cap sections the wall panels and sub-cap section are filled with ultra high performance concrete.

An alternate object of the present invention is to provide a seawall that is installed so as to protect a landform from marine conditions wherein the present invention further includes a top cap member that is placed ensuing the pour of ultra high performance concrete but prior to the curing thereof.

To the accomplishment of the above and related objects the present invention may be embodied in the form illustrated in the accompanying drawings. Attention is called to the fact that the drawings are illustrative only. Variations are contemplated as being a part of the present invention, limited only by the scope of the claims.

BRIEF DESCRIPTION OF THE DRAWINGS

A more complete understanding of the present invention may be had by reference to the following Detailed Description and appended claims when taken in conjunction with the accompanying Drawings wherein:

FIG. 1 is a top perspective view of a wall connection spline of the present invention; and

FIG. 2 is an end perspective view of a wall connection spline of the present invention; and

FIG. 3 is a side perspective view of a wall support piling of the present invention; and

FIG. 4 is an upper end view of a wall support piling of the present invention; and

FIG. 5 is a side view of a wall support piling of the present invention; and

FIG. 6 is a perspective view of a wall panel of the present invention; and

FIG. 7 is an end perspective view of a wall panel with a wall panel connection spline engaged therewith; and

FIG. 8 is an end perspective view of a wall panel with a wall panel connection spline engaged therewith; and

FIG. 9 is a side perspective view of two adjoining wall panels of the present invention; and

FIG. 10 is a side perspective view of two adjoining wall panels being operably coupled with a wall connection spline; and

FIG. 11 is a top view of adjoining wall panels operably coupled with a wall connection spline; and

FIG. 12 is a top perspective view of a wall support piling being inserted into a wall panel; and

FIG. 13 is a top perspective view of a wall support piling being inserted into a wall panel; and

FIG. 14 is a top perspective view of a wall support piling fully inserted into a wall panel; and

FIG. 15 is a top perspective view of a pour plug inserted into a cell of a wall panel; and

FIG. 16 is a detailed view of a cell of a wall panel of the present invention; and

FIG. 17 is a top view of two adjoined wall panels being coupled with a wall connection spline; and

FIG. 18 is a top view of two adjoined wall panels being coupled with a wall connection spline; and

FIG. 19 is an end perspective view of a sub-cap section superposed a wall panel section; and

FIG. 20 is an end perspective view of a sub-cap section superposed a wall panel section; and

FIG. 21 is an end view of a wall panel having a sub-cap section superposed thereon with a pour block ready for positioning; and

FIG. 22 is an end view of a wall panel having a sub-cap section superposed thereon with a pour block positioned at the end of the sub-cap section; and

FIG. 23 is an end view of a wall panel having a sub-cap section superposed thereon with a pour block positioned at the end of the sub-cap section; and

FIG. 24 is a rear view of a wall section having a tie rod extending outward therefrom; and

FIG. 25 is a rear view of a wall section having a tie rod extending outward therefrom; and

FIG. 26 is a top view of a wall section having a tie rod operably coupled thereto; and

FIG. 27 is a perspective view of an exemplary section of the present invention with the wall panel and sub-cap section operably coupled; and

FIG. 28 is a top perspective view of wall panels of the present invention having the sub-cap section secured thereto;

FIG. 29 is an end view of a top cap member in position above a wall panel for securing thereto; and

FIG. 30 is an end view of a top cap member secured to a wall panel; and

FIG. 31 is a top perspective view of a top cap member secured to a wall panel; and

FIG. 32 is a top perspective view of an assembled portion of the seawall of the present invention; and

FIG. 33 is a front perspective view of an assembled portion of the seawall of the present invention; and

FIG. 34 is a rear perspective view of an assembled portion of the seawall of the present invention.

DETAILED DESCRIPTION

Referring now to the drawings submitted herewith, wherein various elements depicted therein are not necessarily drawn to scale and wherein through the views and figures like elements are referenced with identical reference numerals, there is illustrated a seawall 100 constructed according to the principles of the present invention.

An embodiment of the present invention is discussed herein with reference to the figures submitted herewith. Those skilled in the art will understand that the detailed description herein with respect to these figures is for explanatory purposes and that it is contemplated within the scope of the present invention that alternative embodiments are plausible. By way of example but not by way of limitation, those having skill in the art in light of the present teachings of the present invention will recognize a plurality of alternate and suitable approaches dependent upon the needs of the particular application to implement the func-

tionality of any given detail described herein, beyond that of the particular implementation choices in the embodiment described herein. Various modifications and embodiments are within the scope of the present invention.

It is to be further understood that the present invention is not limited to the particular methodology, materials, uses and applications described herein, as these may vary. Furthermore, it is also to be understood that the terminology used herein is used for the purpose of describing particular embodiments only, and is not intended to limit the scope of the present invention. It must be noted that as used herein and in the claims, the singular forms "a", "an" and "the" include the plural reference unless the context clearly dictates otherwise. Thus, for example, a reference to "an element" is a reference to one or more elements and includes equivalents thereof known to those skilled in the art. All conjunctions used are to be understood in the most inclusive sense possible. Thus, the word "or" should be understood as having the definition of a logical "or" rather than that of a logical "exclusive or" unless the context clearly necessitates otherwise. Structures described herein are to be understood also to refer to functional equivalents of such structures. Language that may be construed to express approximation should be so understood unless the context clearly dictates otherwise.

References to "one embodiment", "an embodiment", "exemplary embodiments", and the like may indicate that the embodiment(s) of the invention so described may include a particular feature, structure or characteristic, but not every embodiment necessarily includes the particular feature, structure or characteristic.

Now referring in particular to the Figures submitted herewith, the seawall 100 includes a plurality of wall panel connection members 10 illustrated herein in FIGS. 1 and 2. In a preferred embodiment of the seawall 100 the components thereof discussed herein are manufactured from a material such as but not limited to ultra-high performance concrete or fiber reinforced polymer. It should be understood within the scope of the present invention that alternate materials could be utilized in conjunction with or in place of the aforementioned. The wall panel connection members 10 are manufactured from a durable rigid material such as but not limited to concrete and are configured to operably couple adjacent wall panel members 20 during installation of the seawall 100. The wall panel connection member 10 includes a first end 11 and second end 12. Wall panel connection member 10 includes a center portion 13 having opposing longitudinal lateral edges 14, 15. Integrally formed with the opposing longitudinal lateral edges 14, 15 are the first lateral support member 16 and second lateral support member 17. The first lateral support member 16 and the second lateral support member 17 are perpendicular to the center portion 13. The first lateral support member 16 includes a portion 7 that extends above the upper surface 9 of the center portion 13 and further includes a portion 18 that extends below the lower surface 19 of the center portion 13. The second lateral support member 17 is identically constructed as the first lateral support member 16 creating the distinct H-shape of the wall panel connection member 10. This shape facilitates the operable coupling of adjacent wall panel members 20 as is further discussed herein. It should be understood within the scope of the present invention that the wall panel connection member 10 could be manufactured in alternate lengths so as to be the required length depending upon the height of the wall panel members 20. While a preferred shape is illustrated herein, it is contemplated within the scope of the present invention that the wall panel connection

members **10** could be formed in alternate shapes so as to mateably couple adjacent wall panel members **20**.

Illustrated herein in FIGS. 3 through 5 is the piling member **30** of the present invention. The piling member **30** is configured to be inserted into some of the cells **21** of the wall panel members **20** so as to provide anchoring into the ground. The piling member **30**, specifically the lower end **32** thereof will extend beyond the lower edge **22** of the wall panel member **20** and into the ground of sufficient depth to achieve the desired objective of securing the wall panel member **20** in position in accordance with building code requirements. The lower end **32** of the piling member **30** is tapered in form to facilitate improved penetration into the ground. The piling member **30** includes a center section **34** being integrally formed with a first lateral member **35** and a second lateral member **36**. The first lateral member **35** and the second lateral member **36** are perpendicular to the center section **34**. The perpendicular orientation of the first lateral member **35** and second lateral member **36** creates a first void **37** and a second void **38**. The presence of the first void **37** and the second void **38** allows a space to remain in the cell **21** subsequent to the piling member **30** being inserted into the cell **21**. The first void **37** and second void **38** are filled with ultra high performance concrete towards the end of the installation of the seawall **100** and the presence first void **37** and second void **38** provides an improved structural integrity of the seawall **100** through allowance of ultra high performance concrete to be filled therein. It should be understood within the scope of the present invention that ultra high performance concrete is defined as having a minimum compressive strength of seventeen thousand pounds of pressure per square inch.

The seawall **100** includes utilization of wall panel members **20**. It should be understood within the scope of the present invention that the seawall **100** could employ alternate quantities of wall panel members **20** depending upon the length of the installation of the seawall **100**. There are slight variations in the wall panel members **20** most notably an end wall panel member **28** wherein the end wall panel member **28** only has one connection void **40** on an end thereof. The wall panel member **20** includes a plurality of cells **21** wherein the cells **21** extend intermediate the upper edge **23** and lower edge **24**. The cells **21** are hollow so as to be filled with ultra high performance concrete towards the end of the installation process of the seawall **100**. The cells **21** are square in shape so as to be mateable with the piling member **30** but it should be understood within the scope of the present invention that the cells **21** could be formed in alternate shapes so as to accommodate a piling member **30** of a similar shape. The wall panel members **20** include a first end **26** and a second end **27**. Formed on the ends of the wall panel members **20** is the connection void **40**. The connection void **40** includes a center section **41** and a cross section **42** that are integrally formed to create the connection void **40**. The connection void **40** extends intermediate the upper edge **23** and lower edge **24**. Cross section **42** is perpendicular to center section **41** forming a T-shape for the connection void **40**. The T-shape of the connection void **40** provides a mateable coupling to the wall panel connection member **10** as illustrated herein in FIG. 11. Adjacent wall panel members **20** are operably coupled subsequent being placed end to end wherein the connection voids **40** of each wall panel member **20** are aligned and a wall panel connection member **20** is inserted into each connection void **40** of the adjacent wall panel members **20**. It should be understood within the scope of the present invention that the connection void **40** could be formed in alternate shapes so as to mateably couple

with a wall panel connection member **10** of a similar shape. It should also further be understood within the scope of the present invention that the wall panel member **20** could have alternate quantities of cells **21**.

FIG. 15 illustrates the plug member **50** of the present invention. The plug member **50** is configured to be operably inserted into cells **21**. The plug member **50** is manufactured from a durable rigid material such as but not limited to plastic. The plug member **50** can be employed to either completely inhibit pouring of concrete into a cell or can be positioned near the lower edge **24** so as to provide a bottom to the cell **21** and allow the cell **21** to be filled with ultra high performance concrete. It should be understood that the plug member **50** is formed in a shape so as to be mateable with the cell **21**. Furthermore, it should be understood that the plug member **50** could be positioned within the cell **21** anywhere intermediate the upper edge **23** and lower edge **24** of the wall panel member **20**.

Referring to FIGS. 21 and 22 submitted herewith illustrate the sub-cap member **60** of the present invention. The sub-cap member **60** is configured to be superposed the wall panel members **10** ensuing placement thereof. The sub-cap member **60** is operable to provide a structural tie-in between the wall panel members **20** and the top cap member **70** ensuing a pour of ultra high performance concrete into the seawall **100**. The sub-cap member **60** includes center portion **61** having first leg member **62** and second leg member **63** formed therewith on opposing sides thereof. The first leg member **62** and second leg member **63** are integrally formed with the center portion **61** being on opposing sides thereof. The first leg member **62** and second leg member **63** are perpendicular with the center portion **61** having sections **64** that extend both above and below the center portion **61**. The width of the sub-cap member **60** is such that the sub-cap member **60** can be superposed the upper edge **23** of the wall panel member **20** wherein the sections **64** below the center portion **61** are adjacent the exterior surfaces of the wall panel member **20**. The center portion **61** includes apertures **65** formed therein wherein the apertures **65** are of similar size and shape as the openings to the cells **21**. During the pouring of ultra high performance concrete into the seawall **100** the apertures **65** facilitate the flow of concrete into the cells **21**, which subsequent the filling thereof the concrete will fill the upper void **69** of the sub-cap member **60**. Pour blocks **70** are secured to the ends of the sub-cap members **60** so as to provide containment of the poured ultra high performance concrete during the installation of the seawall **100**.

Referring now to FIGS. 24 and 26, the seawall **100** includes tie-back rod **80**. The tie-back rods **80** are manufactured from a durable material such as but not limited to metal. The tie-back rod **80** is configured to extend rearward from the wall panel members **20** and extend into the adjacent land so as to provide additional anchoring of the seawall **100**. While not particularly illustrated herein it should be understood within the scope of the present invention that the tie-back rod **80** can include an anchor plate on the end thereof distal to the wall panel member **20** so as to bolster the securing to the land mass. The tie-back rod **80** is journaled through aperture **82** and includes section **81** that is disposed within the interior volume of the cell **21**. The section **81** is oriented in a downwards direction and will be enveloped by the ultra high performance concrete during the pouring thereof towards the final step of installation of the seawall **100**. It should be understood within the scope of the present invention that the tie-back rod **80** could be manufactured in alternate diameters and lengths as desired for the intended application of the seawall **100**. It should be further

understood within the scope of the present invention that the tie-back rods **80** could be installed in every wall panel member **20** or only a portion thereof.

Referring now to FIG. 31, the top cap member **70** is illustrated therein. The top cap member **70** is configured to be mateably superposed the sub-cap member **60**. The top cap member **70** is operably coupled to the sub-cap member **60** subsequent the pouring of the ultra high performance concrete but prior to the setting thereof. The top cap member includes upper portion **71** wherein the upper portion is perpendicular to the sub-cap member **60** and has a width that is greater than the sub-cap member **60**. The top cap member **70** includes outer leg members **72, 73** wherein the outer leg members **72, 73** extend downward from the lower surface of the upper portion **71**. The outer leg members **72, 73** are positioned so as to be adjacent the first leg member **62** and second leg member **63** of the sub-cap member **60**. The top cap member **70** further includes inner leg member **74**. The inner leg members **74** are positioned so as to be within the upper void **69** between the first leg member **62** and second leg member **63** and extend the length of the top cap member **70**. The inner leg members **74** extend downward from the lower surface of the upper portion **71**. The position of the inner leg members **74** provide engagement with the poured ultra high performance concrete that fills the upper void **69** which provides an integral coupling of the top cap member **70** resulting in a stronger connection of the top cap member **70** to the sub-cap member **60**. It should be understood within the scope of the present invention that the inner leg members **74** could be formed in alternate shapes and sizes and achieve the desired objective as discussed herein. Furthermore, while two parallel inner leg members **74** are illustrated herein, it should be understood within the scope of the present invention that alternate quantities of inner leg members **74** could be present.

In the preceding detailed description, reference has been made to the accompanying drawings that form a part hereof, and in which are shown by way of illustration specific embodiments in which the invention may be practiced. These embodiments, and certain variants thereof, have been described in sufficient detail to enable those skilled in the art to practice the invention. It is to be understood that other suitable embodiments may be utilized and that logical changes may be made without departing from the spirit or scope of the invention. The description may omit certain information known to those skilled in the art. The preceding description is, therefore, not intended to be limited to the specific forms set forth herein, but on the contrary, it is intended to cover such alternatives, modifications, and equivalents, as can be reasonably included within the spirit and scope of the invention.

What is claimed is:

1. A seawall configured to be installed along a landmass edge adjacent to a body of water wherein the seawall comprises:

at least two wall panel members, said at least two wall panel members having a first end and a second end, said at least two wall panel members having an upper edge and a lower edge, said at least two wall panel members having a plurality of cells wherein the plurality of cells are hollow and extend intermediate the upper edge and lower edge, said plurality of cells having an opening proximate said upper edge, wherein said at least two wall panel members further include a connection void formed on at least one end thereof, said connection void extending between said upper edge and said lower edge of said at least two wall panel members, said connec-

tion void being hollow and having a mateable shape so as to couple to said wall panel connection member; a wall panel connection member, said wall panel connection member being configured to be intermediate said at least two wall panel members, said wall panel connection member configured to operably couple said at least two wall panel members;

at least one piling member, said at least one piling member being elongated in shape, said at least one piling member having a first end and a second end, said at least one piling member being tapered at said second end, said at least one piling member configured to be inserted into one of said plurality of cells;

a sub-cap member, said sub-cap member configured to operably couple to said upper edge of said at least two wall panel members, said sub-cap member having a first end and a second end, said sub-cap member having a center portion wherein the center portion includes a plurality of apertures, said sub-cap member having a first leg member and a second leg member on opposing sides of said center portion, said first leg member and said second leg member being perpendicular to said center portion, said first leg member and said second leg member extending above an upper surface of said center portion so as to create a void, said apertures configured to be aligned with the openings of said plurality of cells so as to allow concrete to be poured therethrough, said void further being configured to retain concrete subsequent pouring thereof into the seawall, wherein said sub-cap member further includes a pour block, said pour block located at said first end of said sub-cap member and said second end of said sub-cap member, said pour block being placed on said upper surface of said center portion of said sub-cap member intermediate said first leg member and said second leg member;

a top cap member, said top cap member configured to be superposed said sub-cap member subsequent pouring of concrete into said at least two wall panel members and into the void of said sub-cap members, wherein said top cap member further includes an upper portion, said upper portion of said top cap member being perpendicular to said sub-cap member; and

at least one plug member, said at least one plug member configured to be inserted into at least one of said plurality of cells, said at least one plug member moved to a position intermediate said upper edge and lower edge of said at least two wall panel members.

2. The seawall configured to be installed along the landmass edge adjacent to the body of water as recited in claim 1, wherein said at least one piling member includes a center section having a first lateral member and a second lateral member contiguous therewith and perpendicular thereto, said at least one piling member being formed so as to form a void intermediate an inner surface of said plurality of cells and said center section so as to allow concrete to be poured therearound.

3. The seawall configured to be installed along the landmass edge adjacent to the body of water as recited in claim 2, wherein said upper portion of said top cap member further include a first outer leg member and a second outer leg member extending downward therefrom, said first outer leg member and said second outer leg member configured to be adjacent an outer surface of opposing sides of said at least two wall panel members ensuing placement of said top cap member.

4. The seawall configured to be installed along the landmass edge adjacent to the body of water as recited in claim 3, and further including at least one tie-back rod, said at least one tie back rod having a portion configured to be placed within one of said plurality of cells, said at least one tie-back rod extending outward from said at least two wall panel members. 5

5. The seawall configured to be installed along the landmass edge adjacent to the body of water as recited in claim 4, wherein said top cap member further includes a first inner leg member and a second inner leg member extending downward from said upper portion of said top cap member, said first inner leg member and said second inner leg member configured to extend into said void of said sub-cap member. 10

6. The seawall configured to be installed along the landmass edge adjacent to the body of water as recited in claim 5, wherein said connection void is T-shaped. 15

7. A seawall configured to be installed along a landmass edge adjacent to a body of water and have concrete poured thereinto subsequent installation of the seawall wherein the seawall comprises: 20

a plurality of wall panel members, said plurality of wall panel members having a first end and a second end, said plurality of wall panel members further having a first side and a second side, said plurality of wall panel members having an upper edge and a lower edge, said plurality of wall panel members having a plurality of cells wherein the plurality of cells are hollow and extend intermediate the upper edge and lower edge, said plurality of cells having an opening proximate said upper edge, said plurality of wall panel members further having a connection void on said first end thereof, said connection void extending between said upper edge and said lower edge, said connection void being hollow having a center section and a cross section, said cross section being integrally formed with said center section and perpendicular thereto; 35

a plurality of wall panel connection members, said plurality of wall panel connection members being configured to operably couple said plurality of wall panel members, said plurality of wall panel connection members mateably shaped with said connection void so as to be inserted thereinto; 40

a plurality of piling members, said plurality of piling members being elongated in shape, said plurality of piling members having a first end and a second end, said plurality of piling members being tapered at said second end, said plurality of piling members configured to be inserted into some of said plurality of cells, wherein said plurality of piling members further include a center section, said center section being planar in manner having a first lateral member and a second lateral member on opposing sides thereof, said first lateral member and said second lateral member being perpendicular to said center section of said plurality of piling members, said center section, said first lateral member and said second lateral member creating a first void and a second void between inner surface of said plurality of cells so as to allow concrete to be poured therearound; 50

a sub-cap member, said sub-cap member configured to operably couple to said upper edge of said at least two wall panel members, said sub-cap member having a first end and a second end, said sub-cap member having a center portion wherein the center portion includes a plurality of apertures, said sub-cap member having a 55

first leg member and a second leg member on opposing sides of said center portion, said first leg member and said second leg member being perpendicular to said center portion, said first leg member and said second leg member extending above an upper surface of said center portion so as to create a void, said first leg member and said second leg member further having portions extending downward from said center portion wherein said portions of said first leg member and said second leg member are adjacent said first side and said second side of said plurality of wall panel members, said apertures of said center portion configured to be aligned with the openings of said plurality of cells so as to allow concrete to be poured therethrough, said void further being configured to retain concrete subsequent pouring thereof into the seawall, wherein said sub-cap member further includes a pour blocks, said pour blocks being rectangular in shape and located at said first end of said sub-cap member and said second end of said sub-cap member, said pour blocks being placed on said upper surface of said center portion of said sub-cap member intermediate said first leg member and said second leg member;

a top cap member, said top cap member configured to be superposed said sub-cap member subsequent pouring of concrete into said at least two wall panel members and into the void of said sub-cap members, said top cap member having an upper portion wherein said upper portion of said top cap member is perpendicular to said sub-cap member, wherein said upper portion of said top cap member further includes a first outer leg member and a second outer leg member extending downward therefrom, said first outer leg member and said second outer leg member configured to be adjacent an outer surface of said first side and said second side of said plurality of wall panel members ensuing placement of said top cap member and wherein said top cap member further includes a first inner leg member and a second inner leg member extending downward from said upper portion of said top cap member, said first inner leg member and said second inner leg member configured to extend into said void of said sub-cap member; and at least one plug member, said at least one plug member configured to be inserted into at least one of said plurality of cells, said at least one plug member moved to a position intermediate said upper edge and lower edge of said plurality of wall panel members.

8. The seawall configured to be installed along the landmass edge adjacent to the body of water and have concrete poured thereinto subsequent installation thereof as recited in claim 7, wherein said plurality of wall panels further include one aperture journaled through the second side thereof, said aperture configured to penetrate into one of said plurality of cells. 55

9. The seawall configured to be installed along the landmass edge adjacent to the body of water and have concrete poured thereinto subsequent installation thereof as recited in claim 8, and further including at least one tie-back rod, said at least one tie back rod having a portion configured to be placed within one of said plurality of cells and journaled through said one aperture of said plurality of wall panel members, said at least one tie-back rod extending outward from said second side of said plurality of said wall panel members. 60

10. The seawall configured to be installed along the landmass edge adjacent to the body of water and have concrete poured thereinto subsequent installation thereof as 65

recited in claim **9**, wherein said plurality of wall connection panels further include a center portion, said center portion having formed on opposing lateral edges a first lateral support member and a second lateral support member, said first lateral support member and said second lateral support member being perpendicular to said center portion. 5

11. The seawall configured to be installed along the landmass edge adjacent to the body of water and have concrete poured thereinto subsequent installation thereof as recited in claim **10**, wherein said plurality of cells and said 10 void of said sub-cap member are filled with ultra-high performance concrete ensuing placement thereof.
